UNITED STATES PATENT OFFICE.

JAMES KREITER, OF FREDERICKSBURG, OHIO.

FLYING-MACHINE.

1,208,984.

Specification of Letters Patent. Patented Dec. 19, 1916.

Application filed June 28, 1913. Serial No. 776,359.

To all whom it may concern:

Be it known that I, JAMES KREITER, citizen of the United States, residing at Fredericksburg, in the county of Wayne 5 and State of Ohio, have invented certain new and useful Improvements in Flying-Machines, of which the following is a specification.

This invention relates to improvements 10 in flying machines, and an object thereof is to provide a machine of this character wherein superimposed sets of lateral oscillatory planes are employed to raise or lower the machine.

Another object of the invention contemplates the provision of a flying machine which is particularly designed and adapted 15 for use in conjunction with operating means which both propels and guides the machine, the machine having a vertically extending mast secured thereto upon which are arranged the oscillatory planes or wings employed for elevating or lifting the machine, the said wings being constructed in such 20 a novel and peculiar manner as to form imperforate lateral planes during the downward stroke thereof and perforate or ineffectual planes during the reverse or upward stroke thereof, this being accomplished by 25 the provision of a plurality of flap valves so arranged upon the planes as to operate automatically during the oscillatory movement.

A further object of the invention resides 30 in the provision of means including a rearwardly extending mast or rod having a plurality of segmental planes arranged thereupon, the planes in question likewise being provided with a plurality of flap 35 valves, thereby permitting forward oscillatory movement of the planes without checking the progress of the machine during flight, the planes or wings being operated from the same source of power as the 40 said lateral planes, and the mast or rod having means employed in connection therewith for swinging the said segmental planes 45 out of axial alinement with the car body to guide or control the direction of flight 50 of the machine.

The invention still further resides in the provision of simple and efficient means for oscillating the lateral as well as the various other planes employed in connection with 55 the invention, the said means being controlled by the rotation of a driven fly wheel,

the wheel having the operating means eccentrically pivoted thereto.

A still further object of the invention is to provide a plurality of alternating auxiliary segmental planes arranged near the top of the vertically extending mast and operated by the same means as the said lateral planes, the former materially assisting in the lifting of the machine as well as maintaining the stability of the machine when in operation.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is a side elevation of a flying machine constructed in accordance with my invention; Fig. 2 is a front view of the machine; Fig. 3 is a top plan view of the auxiliary segmental planes; Fig. 4 is a section on the line 4—4 of Fig. 3; Fig. 5 is a section on the line 5—5 of Fig. 3; Fig. 6 is a detail perspective view of the main or lateral planes illustrating the manner in which the operating rods are connected 90 thereto; Fig. 7 is an enlarged sectional view of the main support illustrating the manner in which the masts are secured thereto; Fig. 8 is an enlarged elevation, partly broken away illustrating the detail arrangement of the flap valves upon one of the lateral planes; Fig. 9 is a section on the line 9—9 of Fig. 8; Fig. 10 is a detail perspective view of one of the valves; Fig. 11 is an enlarged elevation of one of the lifting 95 auxiliary segmental planes; Fig. 12 is a section on line 12—12 of Fig. 11; Fig. 13 is a sectional view of one of the propelling segmental planes.

Referring now to the drawings, wherein 105 is illustrated the preferred form of my invention only the important details have been shown; the machine comprising, first the body portion and the operating mechanism carried thereby, second the main or lateral 110 planes and the operating means employed in connection therewith, third, the auxil-

iary segmental planes arranged above the said lateral planes, and fourth the segmental planes carried by the rearwardly extending mast. A brief description of each will follow in the order named.

In the reduction of my invention to practice, and referring in detail to the drawings, the numeral 1 designates the body portion of the machine, preferably wedge shaped and constructed of suitable light yet strong material, the wide or diverged end extending toward the rear of the machine to offer as little resistance as possible to the air during flight. An engine 2 of the type 10 usually employed in connection with flying machines is arranged upon the deck of the car body 1 having a fly wheel 3 mounted for rotation thereupon, and a forwardly extending shaft 4 is journaled within suitable 15 bearings 5 carried by the body 1 of the machine. A propeller 6 of any suitable construction is mounted for rotation upon the forward extremity of the shaft 4 for driving the machine forward during flight, the 20 rotation of the propeller being controlled by the engine 2 of the machine.

A vertically extending mast 7 is mounted upon a suitable base 8 positioned about midway the length of the machine body 1, the 25 mast 7 terminating at its lower extremity in a ball member 9 adapted to fit within a socket 10 formed within the said base for effecting a universal joint for the mast and permitting the same to oscillate, and in 30 this manner maintain the stability of the machine when in operation. Adjustably secured to the mast 7 is a collar 11 from the 35 opposite sides of which a support rod 12 extends. Pivots secured as at 13 to the extremities of the rod 12 are a pair of cross rods 14 the extremities of which are provided with pins 15 adapted to fit within elongated apertures or slots 16 formed within and extending throughout the major portion 40 of the length of the sides 17 of the lateral or main planes designated in their entirety by the numeral 18. The sides 17 of the planes are pivotally connected as at 45 so as to allow the planes carried by the 50 said sides to oscillate from the said pivot point, the oscillatory movement being controlled by the movement of the cross rods 14 in a manner to be hereinafter fully described.

55 Extending parallel with the mast 7 and supported in such parallel relation through the medium of brackets 20 is an operating rod 21 the lower extremity of which is pivotally secured as at 22 to a connecting rod 60 23 in turn pivotally secured as at 24 to the fly wheel 3 of the engine, the pin 24 being eccentrically disposed upon the said fly wheel for imparting a reciprocatory movement to the rod 21 according to the rotation 65 of the fly wheel 3. A collar 25 is rigidly

secured, in any suitable manner to the operating rod 21, the said rod having pivotally secured thereto as at 26 a pair of links 27, the opposite extremities of which are arranged over a pair of parallel spaced apart 70 rods 29 connecting the cross rods 14 arranged at each end of the lateral planes 18. This arrangement of the operating rod 21 with respect to the rods 29 will cause the cross rods 14 to be swung from their pivotal support 13 for imparting oscillatory movement to the planes 18, the pins 15 working within the slot 16 of the plane sides. Cross rods 14 being centrally pivoted, movement thereof will oscillate the planes in the desired manner. Passing on to the description of the auxiliary supplemental planes, the same being arranged near the upper extremity of the vertically extending mast 7, operation of the said planes is controlled by the reciprocatory movement of the operating rod 21. The upper extremity of the rod 21 is connected to a vertically slidable collar 30 arranged over the mast 7 and to which certain of the segmental planes 31 are secured. A cone shaped member 32 is secured to the mast 7, the said member having slits 33 extending toward the converged end from the base thereof through which rods 34 extend, one extremity of the rods 34 being pivotally secured as at 35 to the said cone member at the diverged end thereof the opposite end having a slidable connection as at 36 and as illustrated in Fig. 4, with the other pair of planes 37 which are 100 in turn pivotally secured as at 38 to a second cone member 39 secured to the mast 7 over and above the first mentioned cone member 32. The rods 34 are adapted to work or pass through eyes 40 carried by the sliding collar 30 so that the said rods may be moved or worked according to the reciprocatory movement of the said collar, this arrangement of the rods with respect to the collar oscillating the planes 37 in the 105 desired manner. The other planes 31 are likewise pivotally secured to the upper cone member 39 as at 41, the operation of these planes being controlled through the medium of rods 42 pivotally connected as at 43 to the reciprocating collar 30 and having their 110 opposite ends arranged in guide members 44 carried by the planes 33 upon the under face thereof, and as the said rods 42 have slideable connection as at 45 with the lower cone member 32 it will be seen that the said planes 31 may be oscillated during the reciprocatory movement of said collar. The planes 31 being disposed oppositely to the planes 37, that is the planes 31 being actuatable to carry out their downward stroke while the planes 37 are actuatable in the opposite direction to carry out their upward stroke, it is apparent that the said planes will at all times offer resistance to the at 115 120 125 130

mosphere and prevent downward movement of the machine.

Coming now to the description of the segmental planes carried by the rearwardly ex-

5 tending mast, the numeral 46 designates the said mast, the same being secured as at 47 to the base 8 in a like manner to that provided for the vertical mast 7. An operating rod 48 extends parallel with the mast 46 the inner 10 end of the rod being universally joined as at 49 to a connecting rod 50 which is in turn eccentrically connected to the fly wheel 3 in the same manner as the connecting rod above mentioned, this arrangement recip- 15 roating the rod 48 in a like manner to that of the operating rod 21 employed in connection with the vertically extending shaft. A guide, as well as a support 51 extends upwardly from the base of the machine through 20 which both the mast 46 and the operating rod 48 extend, the said support having a laterally extending groove formed therein to allow the rod and the mast to be swung out of axial alinement with the car body for 25 controlling the direction of flight of the machine, any suitable means being employed for the purpose of actuating or swinging the rod in the desired manner.

The segmental planes 52 and 53 of the 30 rearwardly extending mast are mounted for operation in the same manner as the planes 31 and 37 above described and for this reason the detail construction of the operating mechanism will not be described. A rudder 35 or vertical plane 54 may be arranged over the rear extremity of the mast 46 to assist in guiding the machine according to the manipulation of the said mast in the manner above set forth.

40 Brace rods 55 are connected at one end to the car body 1 as at 56 the said rods extending from the said body at an angle so as to permit their opposite ends to be connected to the vertically extending mast through the 45 medium of a spring 57, the spring being disposed between the said mast and the opposite end of the rod, this arrangement permitting the mast to move or swing from the universal joint provided therefor to main- 50 tain at all times the stability of the machine.

Emergency operating means is provided for operating the auxiliary segmental planes 31 and 37, the said means comprising a base 58 having an operating lever 59 pivotally 55 secured thereto, the said lever in turn having a rod 60 secured thereto, the opposite end of which is secured to the collar 30 so that the latter may be reciprocated according to the movement of the lever 59. The lever 59 is 60 preferably operated by hand and is adapted to be used only in cases of emergency, should the engine 2 for any reason become inoperative, when the oscillating of the planes 31 and 37, with the resistance afforded 65 by the lateral planes 18 will effectually check

a rapid falling of the machine and will insure a safe landing thereof as well as prevent injury both to the machine and the passengers carried thereby.

The several planes employed in connection with this invention are composed of a plurality or series of flap valves 61 adapted to be hingedly connected as at 62 to uniformly spaced apart parallel rods 63 extending throughout the length of the several planes. 70 The said valves being loosely connected to the rods 63 it will be seen that they will normally depend or hang suspended from the rods so as to allow the air to pass therebetween during the upward stroke of the 75 plane, the resistance offered by the air upon the downward stroke causing the valves to move upwardly until substantially parallel with a screen 64 arranged over the top of the planes, the said valves when in this position 80 providing an imperforate plane and offering a maximum amount of resistance to the air thereby causing the machine to rise during the downward stroke of the several planes. The valves 65 of the planes 52 and 53 are ar- 85 ranged upon the opposite face to those of the various other planes so as to allow the air to pass therethrough during the forward stroke of the planes yet automatically closing the planes and preventing the passage 90 of air therethrough during the rearward stroke of the planes, this action, taken in connection with the pull derived by the rotation of the propeller 6 causes the machine to be propelled in a forward direction, the 100 planes 52 and 53 alternating in their stroke and in this manner causing the machine to move forwardly in a smooth and regular manner.

Having described fully the construction 105 of the machine, it now remains to mention, a little more in detail, the operation of the same. The engine 2 is first started for driving the propeller 6 and the fly wheel 3. As the fly wheel 3 is driven, the operating rod 110 21 is reciprocated by reason of the eccentric pivotal connection afforded between the said rod and the said wheel. The reciprocatory movement of the rod 21 operates the rods 29 which in turn operate the cross rods 14 of 115 the main or lateral planes, and as these rods 14 are pivoted centrally to the stationary or immovable rod 12 it will be seen that the planes 18 are oscillated from their pivotal connection 19 thereby elevating the machine 120 as occasion demands, the flap valves 61 of the said plane being automatically operated during the oscillatory movement thereof. The said operating rod 21 also imparts motion to the reciprocating collar 30 for oscillating the auxiliary segmental planes 31 and 37, the said collar being adapted to engage 125 the operating rods 34 and 42 of the said planes for oscillating them alternately during the movement of the rod 21. The planes 130

52 and 53 are also simultaneously operated by the rotation of the fly wheel 3 of the engine as the said planes are connected thereto through the medium of the rod 48
5 and the connecting rod 50 the former being secured at one end to the reciprocating collar carried by the mast 46, the collar actuating rods connected to the planes for alternately operating the same, thereby propelling the entire machine in a manner desired.
10 The planes 18, as above pointed out, are arranged in pairs, the planes of each pair being pivotally connected at the point 19 whereby to permit of relative simultaneous movement. As the rods 29 are actuated through movement of operating rod 21 it is evident that the cross rods 14 will operate in unison, and by reason of their engagement with the several planes, cause the latter to be correspondingly moved. As the adjacent terminals of the cross rods begin to spread, the pins 15 will be caused to move toward the outer terminals of the slots 16 within which they operate. The rods 14
25 being fixed against displacement at the point 13, and the planes 18 being fixed at the point 19 against separation, such movement of the pins 15 as hereinbefore mentioned, will cause the planes 18 to simultaneously oscillate or
30 swing from a plane which is at an angle to the horizontal to a horizontal plane. It must be remembered that the planes are not fixed against movement at the point 19 but that said point, during oscillation of the planes, will rise and fall to permit oscillatory movement of the cross rods 14. Were the point 19 fixed, then the planes would be incapable of the movement to the extent desired.
35 40 It is to be further noted that with reference to Fig. 2 of the drawings those portions of planes 18 which extend outward beyond the levers 14 present a greater area for the support of the machine than those portions of said planes which extend inward toward the central post. As a result of this arrangement upon the outward movement of the levers 14 toward the position shown in dotted lines and assuming the
45 50 machine will have the effect of causing the planes to rotate upon the pivot 19 because of an upward component of air pressure upon the extremities of the planes and as the levers 14 continue their movement, the planes will assume the position shown in dotted lines. The planes having reached the position stated it will be noted that those portions inward of the levers present a greater area to the air. The exposure of
55 60 this greater area might have the effect of causing the planes to buckle up again were it not for the connection of said links with the central post. However it is to be understood that the rods will be assisted in their reverse movement by the upward pres-

sure of the air upon the lower central portions of the planes when the planes move toward their former positions.

By providing a universal joint or mounting for the vertically extending mast 7 the stability of the entire machine is maintained during flight, while the direction of travel is controlled by swinging the rearwardly extending mast 46 laterally, the said mast being universally connected within the base 8
75 as indicated at 47 in the drawings.

It will be seen from the above, taken in connection with the accompanying drawings that an emergency operating means has been provided for oscillating the planes 31
80 and 37 should the engine for any reason become inoperative; that the flap valves are arranged upon the several planes to operate automatically according to the stroke governed by the operating rods 21 and 46;
85 and that the said planes, when the flap valves are thrown into engagement with the screens provided therefor, are made imperforate and thereby offer great resistance to the air and in this manner elevate the machine or propel the machine as the case may be, in the desired manner.
90

In reduction to practice, I have found that the form of my invention, illustrated in the drawings and referred to in the above description, as the preferred embodiment, is the most efficient and practical; yet realizing that the conditions concurrent with the adoption of my device will necessarily vary,
95 I desire to emphasize the fact that various minor changes in details of construction, proportion and arrangement of parts may be resorted to, when required, without sacrificing any of the advantages of my invention, as defined in the appended claims.
105

Having thus fully described my invention, which I claim as new and desire to secure by Letters Patent, is:—

1. In a flying machine, a mast, superposed cone members affixed to the mast, a plurality of auxiliary segmental planes hingedly connected to the uppermost cone, an operating rod, and a connection between said rod and the several planes, the lowermost cone acting as a guide for the connecting means, substantially as set forth.
110

2. In a flying machine, a vertical mast, a pair of superposed cone members affixed to the mast, a plurality of hingedly connected auxiliary segmental planes carried by the uppermost cone, an operating rod, means to reciprocate the mentioned rod, and means secured to the lowermost cone and actuatable through movement of the operating rod to oscillate the several planes, substantially as described.
115
120

3. In a flying machine, a mast, superposed cones secured to the mast, the lowermost cone being slotted at diametrically opposite points, a plurality of auxiliary segmental
125
130

planes hingedly connected to the uppermost cone, the mentioned planes being arranged in pairs, the planes constituting the respective pairs being disposed at diametrically opposite points, an operating rod, a first pair of connecting rods secured to the lowermost cone and to one pair of the mentioned planes, said rods being engaged by the operating rod to oscillate said planes, a second pair of connecting rods secured to the operating rod and to the lowermost cone and to the other of the mentioned planes to oscillate said planes, and means to reciprocate the operating rod.

4. A flying machine having a vertically extending mast mounted upon the body thereof, a pair of spaced apart cone members rigidly secured to the said mast, a plurality of segmental auxiliary planes hingedly connected to the upper of the said cone members, a slidable collar on said mast below said cone members, rods pivotally secured to the lower of the said cone members and to certain of the said planes, the said rods adapted to be engaged by the said collar, rods secured to the other of the said planes, and to the said collar, the last mentioned rods being pivotally and slidably secured to the lower of the said cone members, means for reciprocating the said collar, such reciprocatory movement adapted to operate all of

the said rods for alternately oscillating the said planes, as and for the purpose set forth.

5. A flying machine including a body portion, a mast mounted thereupon, a pair of spaced apart cone members mounted immovable upon said mast, a plurality of planes hingedly connected to one of said cone members, and means operable upon said mast and engageable with the other of the said cone members to alternately oscillate the said planes, as and for the purpose set forth.

6. In a flying machine, a vertical mast, a pair of superposed cones secured to the mast, the lowermost cone being slotted at diametrically opposite points, a plurality of auxiliary segmental planes hingedly connected to the uppermost cone, a reciprocatory operating rod, and means secured to the lowermost cone and to the auxiliary planes for oscillating said planes through reciprocatory movement of the mentioned rod, the slots aforesaid acting as a guide for the connecting means, substantially as described.

In testimony whereof I affix my signature in presence of two witnesses.

JAMES KREITER.
